UNITED STATES PATENT OFFICE

156,748

CASING FOR A HAND-DRIVEN ADDRESS PRINTING MACHINE

Carl Olof Lamm, Stockholm, Sweden

Application January 18, 1949, Serial No. 309

Term of patent 14 years

(Cl. D64—10)

To all whom it may concern:

Be it known that I, Carl Olof Lamm, a subject of the King of Sweden, residing at Stockholm, Sweden, have invented a new, original, and ornamental Design for a Casing for a Hand-Driven Address Printing Machine, of which the following is a specification, reference being had to the accompanying drawing forming part thereof.

Figs. 1 and 2 are perspective views from opposite sides of a casing for a hand-driven address printing machine, showing my new design.

I claim:

The ornamental design for a casing for a hand-

driven address printing machine, substantially as shown.

CARL OLOF LAMM.
